C. T. PORTER.
MACHINE FOR DRESSING STONE.

No 11 492

Patented Aug. 8, 1854.

UNITED STATES PATENT OFFICE.

CHARLES T. PORTER, OF NEW YORK, N. Y.

STONE-DRESSING MACHINE.

Specification of Letters Patent No. 11,492, dated August 8, 1854.

To all whom it may concern:

Be it known that I, CHARLES T. PORTER, of the city, county, and State of New York, have invented certain new and useful Improvements in Machinery for Dressing Stone; and I do hereby declare that the following is a full, clear, and exact description of the same, reference being had to the accompanying drawings, forming part of this specification, in which—

Figure 1, is a longitudinal section of a machine, constructed according to my invention. Fig. 2, is a section of the rest and part of the hammer, with a side view of the tool stock. Fig. 3, is a top view of the frame in which the hammer and toolstock work. Fig. 4, is an inside view of part of one of the sides of the aforesaid frame, showing the manner in which the tongues on the toolstock fit the grooves in the frame.

Similar letters of reference indicate corresponding parts in the several figures.

The machinery to which my improvements relate, is in its general character, similar to the machine of E. G. Hastings, patented March 14th, 1854, consisting of a cutting tool and hammer working in adjustable ways, and a rest by which the depth of cut is regulated. In Hastings' machine, the adjustment of the ways at different angles, and the maintenance of the proper relation between the rest, the hammer and toolstock, at all angles, is provided for by making the rest of cylindrical form, and the tool stock with a concavity fitting to the said cylinder, and pivoting the ways to the rest, the latter being fixed, so far as the adjustment of the ways, at various angles, is considered. The cylindrical form of the tool stock in that machine is a necessary condition, but this form is productive of no advantage any further than allowing the adjustment of the ways, while it adds considerable expense to the machine, in consequence of the necessity of turning the rest true, and turning out the concavity in the stock. Another disadvantage is, that the absence of a perfectly rigid connection between the ways and rest, is found to cause a racking of all the adjustable portion of the machine during its operation.

The object of the first part of my invention is to obtain all the desirable results that are obtained by Hastings' arrangement, and at the same time to reduce the cost of the machine, by obviating the necessity of a cy-

lindrical turned rest and corresponding tool stock, and to prevent the racking of the adjustable portion, and to this end the nature of this part of my invention consists in attaching the ways rigidly to the rest, so as to form a frame, and furnishing the frame composed of the rest and the ways with journals which fit to suitable boxes in the main framing of the machine, and serve as pivots upon which the rest and ways swing together, so as to allow of their adjustment to direct the motion of the hammer in a line at any desired angle, to the face to be cut; this construction allows the continuous faces of the rest and tool stock to be made flat, which I consider preferable, as it gives the best bearing, or of any form that may be desired.

The object of the second part of my invention is to cause the edge of the tool to be driven by the blow of the hammer, not in the direction of the said blow, but in a line or plane parallel, or nearly so, with the surface intended to be produced, and thereby to give a high degree of smoothness to the said surface; and to cause the tool to sharpen itself by its own operation. The nature of this part of my invention consists in so fitting the tool stock to the ways or their equivalents, or so arranging the same relatively to the hammer that it is capable of a swinging motion, as well as an upward motion, like that given to the hammer, for the purpose of allowing its edge, resting on the surface of the stone, to be carried backward by the feed motion. The blow of the hammer taking place after this backward motion of the tool, in driving the tool stock home to its rest, takes effect in such a way as to drive the edge of the tool forward, instead of into the stone, and thus produce the desired results.

To enable those skilled in the art to make and use my invention, I will proceed to describe its construction and operation.

A, is the bed of the machine, furnished with suitable ways to receive and allow of the horizontal movement of the carriage B, upon which the stone is placed, and supporting two standards C, C', which span it outside the carriage. The standards have both upright sides, in which are upright grooves, the grooves c, c, in the former being to receive two journal boxes a, a, which are suspended from the upper part of the standard, so as to be capable of being raised and lowered, each by a screw D, and

the grooves c', c' , in the latter being to receive the ends of a cross piece E, which is suspended so as to be capable of being raised and lowered by a screw at each end.

5 I construct the journal boxes a, a , by drilling suitable holes in solid cubical heads at the lower ends of the screws D, which are arranged to be moved up and down, without turning, by nuts l, on the screws; this arrangement being cheaper and more durable, 10 as well as affording greater solidity than any other known to me, but I do not design to limit myself to the mode of construction.

15 G, G, H, is a quadrangular frame of cast iron, whose sides G, G, have straight parallel grooves, g, g , to form the ways to receive the hammer J, and tool stock K, the front end of which constitutes the rest which regulates the depth of cut. The face h , of 20 the rest, is a plane surface perpendicular to the direction of the grooves, and at the ends of the rest are journals I, I, which fit the boxes, a, a , before described, as suspended by the screws, D, within the grooves 25 in the sides of the standard C. The frame is supported near its back end by the cross piece E. The hammer J, fits to the ways G, G, in the same manner as in Hastings' machine, and is similarly operated. The 30 tool stock K, differs only from Hastings' in having its front d , and back e , parallel, so as to be capable of fitting, the former, to the face h , of the rest, and the latter, to the face of the hammer, and in having the 35 tongues k , on its sides or ends taper so that only their back parts fit the grooves g , as shown in Fig. 4, their front parts being narrow enough to admit of a considerable swinging motion of the edge of the 40 tool f . The upper sides of the tongue fit close up to the top of the groove g , when the tool stock is driven home to the rest, leaving all the space between the tongue and groove on the lower side, which will be 45 understood by referring either to Figs. 2, or 4.

In carrying out the first part of my invention, the tool stock may be either attached to, or detached from, the hammer, 50 as in Hastings' machine, and the machine operates on the stone in precisely the same manner; but it is obvious, that, in carrying out the second part of my invention, the operation of the tool can only be effected when 55 detached from the hammer. That operation I will now proceed to describe. The tool stock, after the blow of the hammer, and the commencement of the return movement of the same, remains in contact with the rest, 60 as shown in black outline in Fig. 2, until the feed commences and carries the stone backward, when the point of the tool being in contact with the extreme end of the dressed surface of the stone, is carried back 65 with the stone, as illustrated in Fig. 2, where

the red outlines show the position of the tool and stock at the termination of the feed, the distance of which is somewhat exaggerated to show the operation more clearly. When the hammer descends to strike the blow, it comes first into contact with the lower part 5, of the back, e , of the tool stock, and the tool stock and tool may then be considered as a lever of the first order with the point b , at the lower corner of the back side of the tongues for a fulcrum the point of the tool as the point of weight or resistance, and the power, namely, viz:—the blow of the hammer, applied at the point 5; and supposing the fulcrum to be fixed, 70 the point of the tool would have a tendency to rise, but the fulcrum being variable, in consequence of the tendency of the hammer to drive the stock in the line of its blow, the edge of the tool is caused to move 75 in, or nearly in a right line; and that line, with a proper inclination of the ways in which the hammer and tool stock are guided, may be directly in the line of the surface intended to be produced. This has been 80 proved, by the practical operation of the machine, to be the case, as a surface has been produced on the stone in which anything like ridges or furrows in the direction of the line of the edge of the tool, was scarcely 85 perceptible. 90

The tool employed in this machine, may have a straight or curved edge.

The swinging motion of the tool stock, to enable the point of the tool to move back 100 with the feed, and forward when struck by the hammer, may be employed with equal success, whether the rest and tool stock have flat and parallel contiguous faces, and the rest is rigidly attached to the ways, as described, or a cylindrical rest and concave faced tool stock, arranged as in Hastings' 105 machine, be employed.

Instead of making the tool stock with a taper tongue, it may be furnished on either 110 side with a stud, carrying a friction roller, fitting easily in the groove g , in the ways G, G, which will admit of the same movement of the edge of the tool; or the same result may be obtained by furnishing it with 115 studs fitting to the grooves without friction rollers, or by dispensing altogether with tongues or guides at the ends of the stock, and supporting it by a roller attached to the ways underneath, or behind it.

The conditions to be observed in carrying out the invention, are, that the tool stock shall be capable of vibrating, so as to allow the tool to move back when the feed takes place, and of being driven by the hammer, 125 in the direction of the line of the desired surface.

Having thus fully described my invention, I will now state what I claim as my invention, and desire to secure by Letters Patent. 130

I do not claim the employment of a rest, in combination with a hammer and tool stock, working in ways attached thereto; nor do I confine myself to any particular 5 form of rest, but

I claim:—

1. The employment of a rest H, having its face parallel with the contiguous face of the tool stock, when the said rest is rigidly 10 attached to the ways, G, G, in which the hammer and tool stock work, or forms part of the same frame therewith, and when the frame thus formed is provided with, and swings from journals a, a, which fit in journal boxes, suspended or supported in a suitable manner in the main framing of the machine, so that the ways may be adjusted at 15 different angles to the surface desired to be

cut on the stone without changing the relation of the hammer, the tool, and the rest. 20

2. Constructing the tool stock and arranging it relatively to the rest and the hammer, so that it is capable of vibrating, substantially as described, to allow the tool, resting upon the surface of the stone, to be 25 carried back by the feed motion, and to cause it to be driven by the blow of the hammer, not in the line of the direction of the blow, but forward in, or nearly in the line or plane of the surface desired to be produced, as herein fully set forth. 30

CHARLES T. PORTER.
